UNITED STATES PATENT OFFICE

133,945

DESIGN FOR A GAME BOARD

Bertha L. Church, Los Angeles, Calif.

Application June 12, 1942, Serial No. 107,182

Term of patent 14 years

To all whom it may concern:

Be it known that I, Bertha L. Church, a citizen of the United States, residing at Los Angeles, in the county of Los Angeles and State of California, have invented a new, original, and ornamental Design for Game Boards, of which the following is a specification, reference being had to the accompanying drawing, forming part thereof.

The figure is a plan view of a game board, showing my new design.

Portions of the drawing are lined for contrasting colors. The game board is of conventional thickness.

I claim:

The ornamental design for a game board, as shown and described.

BERTHA L. CHURCH.
